United States Patent Office

Des. 187,113
Patented Jan. 26, 1960

187,113

JUG

John B. Campbell, Paramus, N.J., assignor to The Clorox Company, Cincinnati, Ohio, a corporation of Ohio

Application April 30, 1958, Serial No. 50,680

Term of patent 14 years

(Cl. D58—8)

FIG. 3.

FIG. 4.

FIG. 1.

FIG. 2.

Figure 1 is a side elevational view of a jug showing my design.

Figure 2 is a fragmentary elevational view of the same as seen from the right side of Figure 1.

Figure 3 is a top plan view of the same.

Figure 4 is a cross-sectional view of the same taken on the line 4—4 of Figure 1.

The dominant features of my design reside in the portions shown in full lines.

I claim:

The ornamental design for a jug, as shown and described.
